UNITED STATES PATENT OFFICE.

CYRUS W. SALADEE, OF NEWARK, OHIO.

IMPROVEMENT IN PADLOCKS.

Specification forming part of Letters Patent No. **56,616**, dated July 24, 1866.

To all whom it may concern:

Be it known that I, CYRUS W. SALADEE, of Newark, county of Licking, in the State of Ohio, have invented a new and Improved Mode of Constructing Padlocks; and I hereby declare that the following is a full and exact description of the same, reference being had to the accompanying drawings, and to the letters of reference marked thereon.

In the drawings, Figure 1 represents a front view of the lock with the cover removed, showing the general arrangement and construction of the several parts of the same. Fig. 2 is a front or top view of the cover of the lock, showing the arrangement of the key-plate A 1. Fig. 3 is a reversed view of the cover shown by Fig. 2, representing the arrangement of the guard R, attached to the under side of key-plate A 1, ward S, and the device for operating the key-hole cover T by means of the end of the spring J 1; and Fig. 4 represents the key of the lock.

The very material additional expense of our present class of spring-padlocks over the common sliding-bar locks now in general use holds in check that general demand for the spring-locks which would be created if they were so simplified in their construction and cheapened in their manufacture as to compete in the market with the common lock.

While, therefore, the great object I have in view in my invention herein presented is to cheapen the manufacture of spring-padlocks, I at the same time retain all of the advantages now boasted of in the best constructed spring-padlocks of which I have any knowledge.

So extremely simple of construction is the spring-lock herein shown and described that it is virtually composed (independent of the frame, key, and hasp) of but three pieces—the lock-plate B, shield-plate A, and the single spring J. This arrangement of three parts will compose the most complicated lock that can be made under my invention.

I propose manufacturing a cheaper grade of lock than here shown, consisting of simply the lock-plate B and spring J—two pieces only—by discarding the use of the shield-plate A, as hereinafter described.

The lock-plate B, Fig. 1, and as shown by dotted lines in Fig. 2, having the key-stud H passing through it, is substantially the same arrangement shown in my former application, marked "A."

The arrangement and construction of the lock here shown are as follows:

The common frame and hasp of the padlock now in general use I adopt in this lock. The lock-plate B is formed into shape either by being cast or stamped from sheet metal, to the front lower edge of which is rigidly secured the stud F, Fig. 1, and a hole through the center for the key-stud H to pass through. This plate B is now dropped over the key-stud H.

A shield-plate, A, is now formed, as shown by Fig. 1 in yellow shadings, which also is made to drop over the key-stud and rest on the top surface of the lock-plate B. The plate A has cut through it a slot, d 1, of such proportion as to admit of the upward motion of the stud F when the lock-plate B is thrown back; and the upper end of this slot is to serve as a stop for the stud F. To the right in the shield-plate A is cut the key-slot D, of any form that will admit of the action of the key therein, and at the same time protect the back edge of the lock-plate B from being operated upon by any instrument which may be introduced through the key-hole for the purpose of "picking" the lock.

I now form the spring J out of a single piece of brass or steel wire of the requisite strength, and bend it into such shape around the studs E and F that where it rests against the stud F the spring shall tend in the direction of the line 5, and thus keep the lock-plate B at B 1 pressed firmly into the eye of the hasp C, the lower end of the spring J at J 1 to have a downward tendency in the direction of line 7, so as to press firmly against the stud N, Fig. 3, and thereby keep the key-hole cover T in position over the hole when the key is withdrawn from the lock, and the upper end of the spring J to have an upward tendency against the lock end of the hasp C, in the direction of the line 6, so that the hasp shall be thrown up out of the lock when the hook B 1 of the lock-plate B is thrown back.

All spring-padlocks, so far as I know, have a combination of separate springs by which to accomplish what I perform by the peculiar arrangement of this single spring J.

I do not confine or limit my claim to the precise arrangement here shown of this single spring J, nor do I limit myself to the use of wire from which to make this spring, as it may be formed of various shapes and placed in the lock in a variety of ways, and may as

readily be formed of a thin flat piece of steel as of wire.

Where it is not desirable to operate the key-hole cover T in the cheapest class of locks, this spring J need not extend up past the stud F to form the end J 1 for that purpose.

Now, to prevent taking hold of the stud F with an instrument introduced through the key-hole to throw back the lock-plate B, and thereby pick the lock, I place a guard, R, around the left side of the key-hole (see Fig. 3 and dotted lines in Fig. 2) of sufficient depth to rest against the plate A when the lid, Fig. 2, is in position. This guard may be cast solid with the key-plate A 1, Fig. 2, or rigidly attached to the under side of the cover, Fig. 3, or in any other convenient manner.

The construction or arrangement of the key, Fig. 4, and its operation upon the lock-plate B, I will now describe: The peculiar form of the right-hand edge of the lock-plate B, as indicated by the dotted lines 8 8, obviates the necessity of any acute angle, notch, or hook against which to rest the key for the purpose of unlocking the lock, as is now the universal practice of all lock makers and manufacturers.

It will be seen that the only assailable point to pick this lock is through the key-slot D of the shield-plate A. The instrument, being first passed through the key-hole of the lock, can effect nothing toward picking it at any point it can be made to bear. Should the instrument be provided with a hook on the end with which to reach in under the plate A to get at the lock-plate B through the key-slot D, it will avail nothing, because the point of contact of the instrument with the lock-plate presents no surface that can be taken hold of; and then, as if to render the experiment of picking this lock still more impracticable, the arrangement of the wards 9 and 10, Fig. 1, secured to the shield-plate A, over which the key fits and passes, is directly in the way of any instrument which may be introduced into the lock. The novelty of placing the lower wards in the lock upon the shield-plate A and immediately over the tumbler or lock-plate B serves to render the picking of the lock more difficult than if secured to the back of the lock and by the side of the tumbler, as is the case in all other padlocks now in general use.

The key, Fig. 4, of this lock, when a shield-plate, A, is used, has, in addition to the ordinary wards 3 and 4, a hook, 1 2, the point of which turns inward toward the center of the hole in the key. The open space 2 of this hook is the same as the thickness of the shield-plate, which latter is made to pass through it when the key is in action.

To open this lock the key is dropped into the key-hole and turned back until it reaches the highest point of the slot D, when it passes down through the plate A and is turned back toward the opposite end of the slot until the hook comes in contact with the lock-plate B

at or about the point indicated by line K, when the lock-plate B is drawn back and the lock end of the hasp thrown up out of the lock by the spring J.

In the cheaper class of locks of this kind, where the shield-plate is omitted, the slot 2 in the hook 1 of the key is not needed. In every other respect, however, the operation of the key upon the plate B is the same as if the shield-plate A were employed.

The key-hole cover T is acted upon by the lower end of the spring J at J 1, Fig. 1. On the inside of the cover, Fig. 2, I place the plate v, (see Fig. 3,) to which is riveted the key-hole cover T. This plate v has studs N, against which the end J 1 of the spring J presses.

O and X are studs secured to the cover of the lock, to serve as stops for the end of the plate v when the key-hole cover T is sprung either one way or the other.

The keys for these locks may be varied so that one key will not fit and operate any lock but the one for which it is designed by a slight variation of the position and shape of the key-slot D; also, by the use of a variety of thicknesses of the shield-plates A and lock-plates B, and by altering the position of the wards 9 and 10, as well as a variation of position of the ward S in the key-plate A 1, Figs. 2 and 3.

The arrangement of the shield-plate A may be applied to the common sliding-bar padlock with the same advantage as to the one here shown. Therefore I do not limit my claim to the use of this shield-plate in the lock here shown, as I intend using it in all padlocks wherein additional safety is desirable.

Having thus fully described my invention, what I claim as new, and desire to secure by Letters Patent, is—

1. The shield-plate A, with key-slot D, in combination with the lock-plate B and spring J, constructed and operating as described, and for the purposes set forth.

2. The stud F and spring J, as arranged in combination with the lock-plate B, and slot d', and hasp C, and cover T of the key-hole, operating as described, and for the purposes set forth.

3. Arranging the wards 9 and 10 on the shield-plate A, for the purposes set forth, and operating as specified.

4. The key, constructed with hook 1, as described, in combination with key-slot D, and lock-plate B, and spring J, constructed and operating as set forth.

5. The stud F, or its equivalent, in combination with the lock-plate B and spring J, in the manner and for the purpose substantially as shown and described.

CYRUS W. SALADEE.
